UNITED STATES PATENT OFFICE

MAURICE KERR INGOLDBY, OF WESTMINSTER, LONDON, ENGLAND, ASSIGNOR TO INTERNAL COMBUSTION LOCOMOTIVES, LIMITED, OF WESTMINSTER, ENGLAND, A BRITISH COMPANY

LOCOMOTIVE

Application filed July 8, 1926. Serial No. 121,115.

This invention relates to locomotives of the kind having an internal combustion engine and a variable stroke type of hydraulic driving gear comprising one or more pump units driven by the internal combustion engine and one or more motor units which are supplied with liquid under pressure from the pump unit or units and which transmit power to the locomotive driving wheels and has for its object to effect various improvements in locomotives of this kind as will now be described with reference to the accompanying drawings, in which:—

Figure 1 is a diagrammatic sectional view of a locomotive designed in accordance with the invention.

Figure 2 shows diagrammatically an arrangement of gearing and connecting rods for transmitting power from the motor unit 20 of the hydraulic gear to the locomotive driving wheels.

Figure 3 illustrates in vertical section a form of flexible coupling for use between the crank shaft of the internal combustion engine of the locomotive and the pump unit of the hydraulic gear.

Figure 4 shows the pump and motor units of the hydraulic gear the tilting boxes of which are interconnected so that both of them can be adjusted.

Figure 5 represents diagrammatically the cooling system for cooling the internal combustion engine and the liquid in the hydraulic gear.

Figure 6 is an end view of Figure 5.

Figure 7 illustrates in vertical section a fan and its casing for circulating air over the water cooling element of the cooling system illustrated in Figures 5 and 6.

Figure 8 is a sectional plan view of Figure 7.

Figure 9 illustrates in vertical section gearing for driving the fan, a cooling water circulating pump and a hydraulic gear liquid circulating pump.

Figure 10 is a plan of Figure 9.

Figure 11 illustrates diagrammatically the pump and motor units of the hydraulic gear provided with by-pass valves for short circuiting the suction and pressure sides of the

hydraulic gear either by hand or automatically.

Figure 12 is a detail view of a distributor valve which operates in conjunction with one of the by-pass valves in Figure 11 the distributor valve being shown with its operative parts in the position they would occupy when the gear is running in the reverse direction to that represented by the disposition of the parts in Figure 11.

Figure 13 illustrates in vertical section a hydraulic ram for assisting in overcoming the resistance offered to the movements of the tilting box in the pump unit of the hydraulic gear.

Figure 14 illustrates in vertical section a spring operated device for balancing the overhanging weight of the tilting box of the pump unit, and

Figure 15 illustrates pipe connections between the hydraulic gear liquid circulating pump, liquid cooling element and the replenishing valves of the hydraulic gear whereby the back pressure experienced by said pump is used to effect the replenishment of the liquid in the hydraulic gear in the event of a deficiency of liquid arising when the hydraulic gear is running at a comparatively high speed.

1 is the internal combustion engine. 2 is the pump unit of the hydraulic gear and 3 the motor unit thereof. In the locomotive illustrated the internal combustion engine is of the Diesel type and the hydraulic gear is of the Williams-Janney type.

The drive between the motor unit 3 of the hydraulic gear and the locomotive driving wheels 4, 4 is effected by coupling rods 5 (Figure 1) and in Figure 2 by gearing 6, 6 and coupling rods 5*.

A spring coupling 7 is employed between the crank shaft of the internal combustion engine and the pump unit of the hydraulic gear so that cyclic variations in the internal combustion engine are prevented from being transmitted to the hydraulic gear and consequently to the locomotive driving wheels. This coupling (see Figure 3) comprises two members 8, 8¹ one of which is attached to the crank shaft of the internal combustion engine

55

60

65

70

75

100

and the other to the shaft of the pump unit of the hydraulic gear. The said members 8, 8¹ have on their peripheries a number of grooves 9, 9 in which a steel spring 10 made in segments is placed. The drive between the said members takes place across the springs which under normal running conditions are only slightly bent between their unsupported parts between said members. In the event, however, of the internal combustion engine producing a sudden shock as is liable to occur in starting the said springs by reason of their flexibility take up the shock which is expended in further bending the unsupported portions thereof between said members and is consequently not transmitted to the hydraulic gear.

The tilting boxes or swash plates in both the pump unit and the motor unit of the hydraulic gear are made adjustable so that a large starting torque can be obtained when starting the locomotive by suitably adjusting both tilting boxes. The mechanism for effecting the adjustment of the tilting boxes is interconnected and means are provided whereby adjustment to said tilting boxes can be made from either end of the locomotive. This is accomplished (see Figure 4) by providing a bevel wheel 11 on the shaft 12 of the pump unit 2 (which is the shaft usually provided for effecting the adjustment of the tilting box 2^x). Engaging with the bevel wheel 11 is a bevel wheel 13 secured to a shaft 14 rotatably mounted on the casing of the pump unit. A shaft 15 is similarly mounted on the motor unit 3 and engages by means of a worm 16 with a worm wheel 17. This worm wheel is formed with a cam surface 18 with which engages a pin 19 on an arm 20 which transmits movement to the tilting box 3^x of the motor unit. The said shafts 14 and 15 are interconnected by means of a shaft 21. The shafts 12 and 15 are extended as shown at 22 and 23 and suitably formed for the reception of gear wheels or other mechanism whereby they can be rotated. By a suitable system of extended shafts 22^x, gearing 23^x, etc., (see Fig. 1) movement can be transmitted to either the shaft 22 or the shaft 23 from hand wheels 24^x, 25^x situated at either end of the locomotive and controlled by the driver thereof, this movement being transmitted to the tilting boxes in both the pump unit and motor unit by means of the interconnecting mechanism above described.

The internal combustion engine is cooled by water circulated by a pump 24 (see Figure 5) through a water cooling element consisting of radiators 25, 25 and the hydraulic gear by circulation of the liquid used therein (which in this case is oil and hereinafter referred to as "motive oil") through an oil cooling element consisting of two coolers 26, 26 by means of an oil circulating pump 27, which is preferably a variable stroke pump

of the Williams-Janney type. This oil circulating pump also serves by means of oil pipe line 27^x to circulate lubricating oil to the locomotive bearings and other parts which require lubricating by circulating oil. Cooling air is forced over the radiators 25, 25 by means of a fan 28. 29 is the cooling water outlet pipe from the water jacket of the internal combustion engine and 30 is the inlet pipe thereto which pipe communicates with the exhaust side of the water circulating pump 24, the inlet side of said pump communicating with the radiators 25, 25 by means of a pipe 31. The oil coolers 26, 26 have the lower ends of their water spaces connected by a pipe 32 whilst the upper ends of their water spaces are connected respectively to the internal combustion engine outlet pipe 29 and the radiators 25, 25, the latter connection being effected by a pipe 33. For the purpose of replenishing the cooling water owing to loss by evaporation etc., an auxiliary tank 34 is provided which is in communication with the radiators by pipes 35, 36. A pump 37 in the pipe 35 enables water to be lifted from the auxiliary tank into the radiators when it is required to replenish the water therein. The pipe 36 serves as an overflow pipe from the radiators into the said auxiliary tank. The motive oil from the hydraulic gear passes through the pipes 38, 39 into the tank 40 from which it is pumped by the oil circulating pump 27 through the oil coolers 26 and pipe 41, into a tank 42 situated above the radiators. From this tank the cooled motive oil flows back to the hydraulic gear through the pipe 43 under the influence of gravity. The aforesaid tank 40 is situated as low down as conveniently possible so as to prevent air locks and also to enable the motive oil to settle so that it is not drawn by the oil circulating pump in a state of turbulence. By the above arrangement the motive oil of the hydraulic gear is initially heated by the hot cooling water from the engine and is subsequently cooled thereby and maintained at a predetermined temperature substantially that of the hot cooling water from the engine.

Control 27^a is preferably of the screw and nut type, whereby the inclination of the tilting box of the pump 27 may be adjusted by the driver to give such output as is required for efficient lubrication, cooling and circulation of the oil for the hydraulic gear.

The said motive oil circulating pump 27 is provided with means whereby its delivery can be varied so that the temperature of the motive oil in the hydraulic gear can be varied by controlling the rate of flow through the motive oil coolers thereby enabling the temperature of the hydraulic gear to be kept at the most suitable value depending upon the running conditions of the hydraulic

gear, such means consisting of a hand-controlled wheel 27a (see Figs. 1 and 10) adapted to vary the inclination of the tilting box in the pump 27, so that its delivery may be altered. The said motive oil circulating pump also serves to provide forced replenishment of motive oil to the suction or negative pressure side of the hydraulic gear which becomes necessary when it is attempted to run the latter at comparatively high speeds, the necessary pressure to effect this being obtained by the resistance offered to the circulation of the motive oil through the oil coolers or from the resistance offered by valves provided for the purpose. This is accomplished by means of a branch pipe 53 (see Figs. 1 and 15) situated between the pressure side of the motive oil circulating pump 27 and the suction side 20 of the active oil system of the hydraulic gear. Under normal conditions it is found that the resistance offered to the flow of the motive oil through the oil coolers 26 is sufficient to set up a pressure in the pipe high enough to cause motive oil to enter the hydraulic gear in the event of a deficiency occurring therein. In some cases a valve 54 may be arranged in the motive oil discharge pipe whereby the resistance in the pipe 53 can be 25 further increased and a larger volume of motive oil supplied through the said pipe.

The fan for forcing air over the radiators is arranged in a casing 28^x (see Figures 1, 7 and 8) which has stationary blades 28^{xx} 30 and the rotating blades 28^{xx} are driven from the internal combustion engine 1 through suitable gearing and a slipping device. The gearing comprises toothed wheels 44, 45 and 46 (see Figures 1, 9 and 10) which transmit motion from the shaft connecting the internal combustion engine with the pump unit of the hydraulic gear to a shaft 47 arranged above the pump unit 2 of the hydraulic gear which shaft transmits motion to the spindle 48 of the fan through crown wheels 49 and 50. The slipping device is in the form of a plate clutch 51 arranged on the said shaft 47 so that sudden shocks which are experienced by the toothed wheels 44, 45 and 46 are not transmitted to the shaft 47. The said shaft 47 in addition to transmitting motion to the fan also serves to transmit motion to the aforesaid cooling water and motive oil circulating pumps 24, 27. For this purpose the said shaft is provided with toothed wheels 47^x, 47^{xx} (see Fig. 10) which engage with corresponding toothed wheels on shafts 51, 52 arranged on either side of the said shaft 47 and parallel therewith. The shaft 51 serves to drive the motive oil circulating pump 27 and the shaft 52 the cooling water circulating pump 24. By driving the cooling water and motive oil circulating pumps from the shaft 47 these pumps are safeguarded against sudden shock

from the internal combustion engine by the aforesaid clutch 51.

Means under the control of the driver of the locomotive are provided whereby the suction and pressure sides of the hydraulic gear can be short circuited. These means preferably comprise a by-pass valve 53a (see Figure 11) having two ports 54a, 55, communicating respectively with the suction and pressure sides of the motor unit 3 of the hydraulic gear by pipes 56 and 57. Within the casing of the by-pass is a balanced sliding piston valve having two pistons 58, 59 at opposite ends of a common piston rod 60. The piston rod passes through one end of the casing of the by-pass and is adapted to be connected by suitable rods 63^x and levers 64^x to levers 65^x at each end of the locomotive under the control of the driver. By longitudinally displacing the said piston rod 60 the said pistons can be moved into a position where one of them covers the port 55 (as shown in the figure) in which position no passage of motive oil from the motor unit through the by-pass can take place and the motor unit operates in the ordinary manner. By displacing the said piston rod in the opposite direction however the port 55 can be uncovered by the piston 59 thereby permitting motive oil from the pressure side of the motor unit to be released into the suction side via the said by-pass which results in a short circuiting of the suction and pressure sides of the motor unit which consequently ceases to transmit power. For the purpose of retaining the said pistons 58, 59 in their port opening or closing positions a locking device 61 is provided comprising a spring controlled plunger 62 adapted to enter one or the other of grooves 63, 64 formed in the extension of the piston rod 60, said grooves being so positioned that one or the other of them is entered by the spring controlled plunger when the pistons are moved into position for either opening or closing the said port 55. By means of this hand controlled by-pass valve creeping of the motor unit can be prevented when the locomotive is standing at a station by short circuiting the suction and pressure sides of the motor unit; also the locomotive can be moved by power other than its own when the by-pass valve is moved into its short circuiting position.

Means are also provided to safeguard against excessive pressure taking place in the hydraulic gear. These means comprise a by-pass valve 65 (see Figure 11) similar to that above described but adapted to be automatically moved into the short circuiting position by the excess pressure in the hydraulic gear. The said by-pass has two ports 66, 67 which communicate by pipes 68, 69 respectively with the suction and pressure sides of

the motor unit 3. The pistons 70, 71 of the by-pass are connected by a common piston rod 72, as in the previously described by-pass 53. At one end of the by-pass is arranged a casing 73 into which the piston 70 extends. The portion of the piston extending into the casing 73 is made hollow for the reception of a flanged plug 74 which constitutes a closure for the casing. The said plug 74 is bored out to contain a ram 75 adapted under certain circumstances to press against the piston 70 and displace the pistons in the by-pass. A spring 76 is arranged round the extended portion of the piston 70 between a flange 70¹ thereon and a suitable part of the by-pass casing and acts to retain the pistons 70, 71 in a position to close the port 67. The said plug 74 communicates by means of a pipe 77 and relief valves 78, 79 with the suction and pressure sides of the pump unit 2 of the hydraulic gear. In the event of an excess pressure arising in the pump unit beyond that determined by the setting of the relief valves 78, 79 motive oil passes one or other of these valves according to the direction of running of the hydraulic gear and enters the aforesaid member or plug 74 by means of the pipe 77 and a passage 80 in the plug 74 and displaces the ram 75 in a direction which causes it to move the pistons 70, 71 into a position whereby the port 67 is uncovered, the result being a short-circuiting between the suction and pressure sides of the motor unit which thereby is relieved of the excess pressure. On pressure ceasing to act upon the ram 75 the pistons are moved back into their normal position to close the port 67 by the aforesaid spring 76 and the pump unit operates at its normal pressure. The said piston rod 72 extends through the opposite end of the by-pass casing to which the said casing 73 is situated and is provided with suitable means whereby it can be interconnected with the locomotive brake mechanism so that when the brakes are applied the said pistons 70, 71 are displaced into a position to establish communication between the ports 66, 67 and short circuit the suction and pressure sides of the motor unit. To enable the displacement of the pistons 70, 71 to take place when the locomotive brake mechanism is operated the piston rod 72 is provided with a finger 72^x with which a projection 73^x on a rod 74^x is adapted to engage. The rod 74^x is connected to the locomotive brake lever 75^x so that when the latter is displaced to apply the brakes 75^{xx} the rod 74^x is moved in the direction indicated by the arrow causing the projection 73^x to bear against the finger 72^x and displace the pistons 70, 71 to establish communication between the ports 66, 67 and short circuit the suction and pressure sides of the motor unit as aforesaid.

Means are also provided to safeguard against the undesirable effect which is likely

to take place in the event of the locomotive over-running the hydraulic gear which might happen when for example the locomotive is proceeding downhill. These means comprise a distributor valve 80 (see Figures 11 and 12) operating in conjunction with the above described automatically controlled by-pass. The distributor valve 80 is a three ported valve, two of which ports are in communication with the suction and pressure sides of the pump unit 2 of the hydraulic gear by pipes 81, 82 respectively, the third port being in communication with the aforesaid plug 74 appertaining to the by-pass 65 by a pipe 83. The said ports in the distributor valve are controlled by a sliding piston valve 84 which is adapted to be displaced by a lever 85 actuated by a pin or roller 85^x carried thereby engaging in a cam surface 2^{xx} formed in a port carried by the tilting box 2^x of the pump unit 2 of the hydraulic gear is moved into position for forward or reverse running so that in either case the port in the distributor valve which communicates with the pressure side of the pump unit is closed and communication is established between the suction side of the pump unit and the aforesaid ram 75 in the by-pass 65. Thus the lever 85 is displaced with the said tilting box. In the event of overrunning of the hydraulic gear taking place the momentum of the locomotive tends to drive the motor unit which then commences to act as a pump and pressure is generated in what are at the time of over-running the suction sides of the motor and pump units and this pressure is conducted to the aforesaid ram 75 through the distributor valve and pipe 83. The ram then operates to move the pistons 70, 71 in the by-pass valve 65 into a position where short-circuiting between the suction and pressure sides of the pump unit occurs thereby preventing the latter from driving the locomotive engine which would be the case otherwise. In Figure 11 for sake of clearness the pump or negative pressure and their delivery or motor units are shown diagrammatically and their suction and pressure ports are indicated by the segmental ports Sa, Sb, Pa, Pb, respectively. In the actual gear the ports Sa and Sb would be in communication with each other and similarly the ports Pa, Pb.

Means are provided to assist in overcoming the resistance offered against movement of the tilting boxes in the pump and motor units of the hydraulic gear, said means comprising a number of pistons 86 one of which is shown in detail in Figure 13 operating in cylinders 87 arranged between a fixed part of the hydraulic gear and the tilting boxes of the pump and motor units 2 and 3 respectively thereof. The said cylinders communicate with the valve-plate ports of the hydraulic gear by passages 87^x. The said pistons have

5 piston rods 88 the outer ends of which are connected to the tilting boxes at or near their peripheries by means of ball and socket joints 89. The piston rods 88 in the motor unit are surrounded by spiral springs 90 which react between a flanged member 91 on the piston rods and an abutment on the exterior of the cylinders 87 to balance the resistance offered against movement of the tilting box due to 10 its overhanging weight. In the case of the pump unit a similar but external device is used in which the overhanging weight of the tilting box is balanced by springs 92 (see Figure 14) operating between a member 93 on a rod 94 which is attached to a crank 95 on the tilting box trunnions and the closed end of a casing 96 surrounding said spring and pivotally attached by a bracket or plate 97 to a suitable fixed part of the hydraulic gear.

20 What I claim and desire to secure by Letters Patent of the United States is:—

1. A locomotive consisting in the combination of an internal combustion engine, an 25 hydraulic gear comprising a pump unit and a motor unit, driving wheels for said locomotive, means for driving the pump unit from the engine, means for transmitting power from the motor unit to the locomotive driving 30 wheels cooling water for said engine, and means for utilizing the cooling water of the engine for cooling the motive oil of the hydraulic gear.

35 2. A locomotive consisting in the combination of an internal combustion engine, an hydraulic gear comprising a pump unit and a motor unit, driving wheels for said locomotive, means for driving the pump unit from the engine, means for transmitting power 40 from the motor unit to the locomotive driving wheels, an element for cooling the cooling water of the engine, and means for utilizing the cooling water of the engine for cooling the motive oil of the hydraulic gear on its way to said element.

45 3. A locomotive consisting in the combination of an internal combustion engine, an hydraulic gear comprising a pump unit and a motor unit, driving wheels for the locomotive, means for driving the pump unit from the engine, means for transmitting power from the motor unit to the locomotive driving wheels, a water cooling element in communication with the water jacket of the engine, an element for cooling the motive oil of the 50 hydraulic gear and means for circulating the water through said elements and water jacket.

55 4. A locomotive consisting in the combination of an internal combustion engine, an hydraulic gear comprising a pump unit and a motor unit, driving wheels for the locomotive, means for driving the pump unit from the engine, means for transmitting power from the motor unit to the locomotive driving 60 wheels, a water cooling element in com-

munication with the water jacket of the engine, an element for cooling the motive oil of the hydraulic gear, means for circulating the water through said element and water jacket and means for circulating air over the water cooling elements.

5. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, a water cooling element in communication with the water jacket of the engine, an element for cooling the motive oil of the hydraulic gear, means for circulating the water through said element and water jacket, a fan for circulating air over the water cooling element and means for driving said fan from the engine.

6. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, driving wheels for said locomotive, a water cooling element in communication with the water jacket of the engine and with an oil cooling element for cooling the motive oil of the hydraulic gear, means for circulating the water through said element and water jacket, a fan, for circulating air over said water cooling element and means for driving said fan through a slipping device located between the engine and the fan.

7. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, an element for cooling the motive oil of the hydraulic gear, a water cooling element in communication with the water jacket of the engine and with said first element, means for circulating the water through said elements and water jacket, a fan for circulating air over said water cooling element, a shaft arranged longitudinally of the hydraulic gear, driving means at one end of said shaft for transmitting motion to said fan and a clutch at the opposite end of said shaft for connecting it with a second shaft driven from the engine.

8. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving 125 wheels, a water cooling element in com-

wheels, an element for cooling the motive oil of the hydraulic gear, a water cooling element in communication with the water jacket of the engine and with said first element, means for circulating the water through said element and water jacket, a fan for circulating air over said water cooling element, a drive shaft arranged longitudinally of the hydraulic gear, a second shaft driven by the engine, driving means at one end of said drive shaft for transmitting motion to said fan, a clutch mounted on said drive shaft for connecting the latter to said second shaft, a pump for circulating the cooling water through the water jacket of the engine and the said cooling elements, and means for driving said pump from said drive shaft.

9. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, a pump for circulating the motive fluid of the hydraulic gear, and means for varying the delivery of said fluid from the said circulating pump.

10. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, an element for cooling the motive oil of the hydraulic gear, a water cooling element in communication with the water jacket of the engine and with said first element, means for circulating the water through said elements and water jacket, an auxiliary tank communicating with the water cooling element and means for supplying water from the auxiliary tank to the water cooling element.

11. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, a by-pass having its ports in communication with the suction and pressure sides of the motor unit, a piston valve in said by-pass and means under the control of the driver of the locomotive for moving said piston valve into a position for opening or closing said by-pass.

12. A locomotive consisting in the combination of an internal combustion engine, an hydraulic gear comprising a pump unit and a motor unit, driving wheels for said locomotive, means for driving the pump unit from the engine, means for transmitting

power from the motor unit to the locomotive driving wheels, means for short-circuiting the pressure and suction sides of the hydraulic gear and means for automatically operating the short-circuiting means in the event 70 of over-running of the hydraulic gear.

13. A locomotive consisting in the combination of an internal combustion engine, an hydraulic gear comprising a pump unit and a motor unit, driving wheels for said locomotive, means for driving the pump unit from the engine, means for transmitting power from the motor unit to the locomotive driving wheels, a by-pass having its ports in communication with the suction and pressure sides 80 of the motor unit, a piston valve in said by-pass, a cylinder at one end of said by-pass, a ram in said cylinder for operating said piston valve, relief valves in communication with the suction and pressure sides of the 85 motor unit and pipe connections between the cylinder and the relief valves.

14. A locomotive consisting in the combination of an internal combustion engine, an hydraulic gear comprising a pump unit and a motor unit, driving wheels for said locomotive, tilting boxes in the pump and motor units, means for driving the pump unit from the engine, means for transmitting power from the motor unit to the locomotive driving wheels, a by-pass having its ports in communication with the suction and pressure sides of the motor unit, a piston valve in said by-pass, a cylinder at one end of said by-pass, a ram in said cylinder for operating the piston valve and means operating in conjunction with the movement of the pump unit tilting box for establishing communication between the cylinder and the suction side of the pump unit during both forward and reverse running of the hydraulic gear.

15. A locomotive consisting in the combination of an internal combustion engine, an hydraulic gear comprising a pump unit and a motor unit, driving wheels for said locomotive, tilting boxes in the pump and motor units, means for driving the pump unit from the engine, means for transmitting power from the motor unit to the locomotive driving wheels, a by-pass having its ports in communication with the suction and pressure sides of the motor unit, a piston valve in the by-pass, a cylinder at one end of the by-pass, a ram in the cylinder for operating the piston valve, a distributor valve in communication with the cylinder and the suction sides of the pump unit operated by the movement of the pump unit tilting box to close the pressure side of the pump unit and establish communication between the suction side 115 thereof and the cylinder according to the direction of running of the hydraulic gear.

16. A locomotive consisting in the combination of an internal combustion engine, a hydraulic driving gear comprising a pump 130

unit and a motor unit, driving wheels for said locomotive, means for driving the pump unit from the engine, means for transmitting power from the motor unit to the locomotive driving wheels, cooling water for cooling the said engine, and means for utilizing the cooling water of the engine to heat initially and subsequently cool the motive oil of the hydraulic gear.

- 10 17. A locomotive consisting in the combination of an internal combustion engine, a hydraulic driving gear comprising a pump unit and a motor unit, driving wheels for said locomotive, means for driving the pump unit from the engine, means for transmitting power from the motor unit to the locomotive driving wheels, water for removing the excess heat developed by said engine, and means for utilizing the resultantly heated water of
15
20 the engine to heat initially the motive oil of the hydraulic gear.
